UNITED STATES PATENT OFFICE.

FRANK R. BAIER, OF CHICAGO, ILLINOIS, ASSIGNOR TO OLIVER M. BURTON, OF CHICAGO, ILLINOIS.

DESIGN FOR A TOY CAR.

55,009.

Specification for Design.

Patented Apr. 27, 1920.

Application filed May 8, 1919. Serial No. 295,777. Term of patent 14 years.

To all whom it may concern:

Be it known that I, FRANK R. BAIER, a citizen of the United States, residing at Chicago, in the county of Cook and State of Illinois, have invented a new, original, and ornamental Design for Toy Cars, of which the following is a specification, reference being had to the accompanying drawing.

The figure is a perspective view of a toy car showing my new design.

I claim:—

The ornamental design for a toy car, as shown.

In testimony whereof I affix my signature.

FRANK R. BAIER.
